FRANK O'BRIEN, OF CANTON, OHIO, ASSIGNOR OF ONE-HALF TO HOWARD G. BEST, OF CANTON, OHIO.

ARM REST.

Application filed September 28, 1926. Serial No. 138,191.

The invention relates to arm rests adapted to be detachably connected to the edge of a desk table or the like to provide a substantial rest for the arm and wrist when 5 writing upon paper or books placed close to the edge of the table.

The objects of the improvement are to provide an arm rest which may be quickly and readily attached to or detached from the 10 edge portion of a desk, table, or book; to provide an adjustable spring clamp for attachment to the table portion of the desk, and a hinged or pivoted plate upon said clamp portion adapted to be swung in any 15 desired position to accommodate the arm and wrist, means being provided upon the clamp portion of the device for bracing the pivoted rest plate and sustain the weight of the arm.

An embodiment of the invention thus set 20 forth in detail is illustrated in the accompanying drawing forming part hereof in which:—

Figure 1 is a perspective view of the improved arm rest;

Fig. 2, a longitudinal sectional view 25 through a portion of the same showing the attachment of the device to a desk; and

Fig. 3, a similar view of a modified form 30 of the invention.

Similar numerals refer to similar parts throughout the drawing.

The device comprises the clamp portion indicated generally at 1 and including a metal plate rounded at one end as shown 35 at 2 the opposite end being bifurcated to form the spaced fingers 3 arranged to rest upon the top of the table portion of a desk or the like as shown at 4.

Between the fingers 3 is a down turned 40 lug 5 which may be bent outward at right angles as shown at 6 in Fig. 3 to clamp beneath the table portion of the desk and which, as desired, may be provided with an offset portion 7 for clamping beneath a wider table portion.

As shown in Figs. 1 and 2 the clamp may be made adjustable by providing the substantial L-shaped bar 8 provided with a vertical bar 9 to receive the clamping bolt 10, 45 extended through the lug 5. With this con-

struction the clamp may be adjusted to fit tables of varying thickness and the thumb 11 is tightened to hold the clamp in adjusting position.

The rest portion of the device comprises an 55 elongated plate 12 the inner end of which is preferably rounded as shown at 13. At the center of the circle described by this rounded end of the rest plate is provided a pivot 14, pivotally connecting the rest plate 60 to the clamp member 1.

For the purpose of bracing this arm plate against the weight of the arm, tangs 15 may be bent upward and backward from the clamp plate 1, between the fingers 3 and the 65 depending lug 5, said tangs being bent down over the rounded edge of the rest plate to brace the same in any position to which the plate is turned.

In the event the user has his desk or table 70 littered with books, papers or the like and desires to sign some papers, checks or similar documents it is only necessary to attach the arm rest to the edge portion of the desk to accommodate the arm and wrist while the 75 papers to be signed may be placed upon the table near to the arm rest.

I claim:

1. An arm rest comprising a clamp portion arranged to be clamped to the table of a desk 80 or the like, an arm rest plate pivotally connected to the clamp portion and tangs upon the clamp portion extended over the end of the arm plate for bracing the same.

2. An arm rest including a clamp portion 85 comprising a plate having spaced fingers arranged to rest upon the top of the table portion of a desk or the like, a depending portion between the fingers having an angular end portion for engagement under the table 90 of the desk and an arm rest plate pivotally mounted upon said clamp plate and tangs upon the clamp plate between said spaced fingers and said depending portion and extended over the end of the arm rest plate for 95 bracing the same.

In testimony that I claim the above, I have hereunto subscribed my name.

FRANK O'BRIEN.
